UNITED STATES PATENT OFFICE.

FRANK M. LEAVITT, OF SMITHTOWN, NEW YORK, ASSIGNOR TO E. W. BLISS COMPANY, OF BROOKLYN, NEW YORK, A CORPORATION OF WEST VIRGINIA.

AUTOMOBILE TORPEDO.

1,108,196.

Specification of Letters Patent. Patented Aug. 25, 1914.

Application filed August 21, 1912. Serial No. 716,189.

To all whom it may concern:

Be it known that I, FRANK M. LEAVITT, a citizen of the United States, residing in Smithtown, in the county of Suffolk and 5 State of New York, have invented certain new and useful Improvements in Automobile Torpedoes, of which the following is a specification.

The present invention relates to automobile torpedoes, and aims to improve the after-body and tail section.

The improvements relate to the construction of the propeller shaft whereby the exhaust air is caused to escape through the 15 inner shaft, and to the lubrication of these shafts.

In the Whitehead torpedo it has been customary to exhaust the air from the engine cylinders into the crank casing and thence 20 through the tubular inner propeller shaft, from which the air escapes at the stern. In the Bliss-Leavitt torpedo, as constructed prior to the present invention, the exhaust air from the turbine motor has passed into 25 the after-body which thus forms an exhaust air chamber, the air forcing itself out therefrom past a spring-pressed valve into an enlarged tail section of the inner propeller shaft, the air escaping from this shaft at the 30 stern as before. This construction is shown in my Patent No. 748,759, dated January 5, 1904. The function of the spring-pressed valve is to close at the end of a practice run and prevent the inflow of water and the 35 consequent sinking of the torpedo.

The present invention introduces one or more spring-closed exhaust valves in openings in a bulkhead between the exhaust air-receiving chamber in the after-body and an 40 adjoining chamber in the tail section; from the latter chamber the air passes through perforations in the inner and outer shafts where they traverse this chamber, and enters the inner shaft, through which it passes to 45 the stern where it escapes. The presence of the spring-pressed valves causes a slight back-pressure in the exhaust receiving chamber; this pressure is utilized to expel lubricating oil from a reservoir thereof 50 through suitable ducts or passages to the bearings of the propeller shafts, whereby a forced lubrication is afforded for these bearings.

The preferred embodiment of the invention is shown in the accompanying drawings, wherein—

Figure 1 is a longitudinal vertical mid-section of the middle portion of the torpedo, the tail section being shown in elevation. Fig. 2 is a longitudinal mid-section of the 60 tail section and an adjacent portion of the after-body, being drawn to a larger scale.

In the drawings A is the torpedo hull or shell, B is the compressed air reservoir, C is the turbine or other motor, D and E are the 65 inner and outer propeller shafts through the after-body, and D' and E' are the continuations of these respective shafts through the tail section, the portions D' and E' being enlarged and both being made tubular. 70 The turbine C drives the shafts D, E, through any suitable gearing, the precise nature of which is immaterial to this invention. The compressed air is conducted from the reservoir B to the motor C in any usual 75 manner, as, for example, through a conduit "a", between which conduits is introduced a reducing valve b. Any usual starting valve c may be provided. The torpedo hull is commonly divided transversely into sections united by screws or otherwise; of these the section A¹ is the after-body and A² is the tail section, the latter commonly including the portion of the hull which carries the propellers, the rudders and the rudder fins. 80 The hull is divided at suitable intervals by transverse bulkheads which may be coincident with the divisions between the sections or otherwise; of these bulkheads the drawing shows only the bulkhead d through 85 which the air enters by suitable nozzles to the turbine; and the bulkhead e at the junction between the after-body and tail section; and the bulkhead f which closes off the tail section. The space between the 90 bulkheads d and e constitutes the exhaust receiving chamber F. The space between the bulkheads e and f constitutes an exhaust chamber or passage G. These chambers communicate through one or more openings 100 in the bulkhead e, these openings being provided with rearwardly opening spring-pressed check valves g. These valves g (of which only one is shown) may be variously constructed, being shown as having a stem 105 with a helical spring coiled upon it. The

function of the valves *g* is to open with the flow of exhaust air, remaining open during the run and closing when this flow ceases at the end of the run in order to prevent an inflow of water which would sink the torpedo; these valves also serve to maintain a slight back-pressure in the chamber *F* which is utilized for purposes of lubrication, as will be explained.

10 The stern section *D'* of the inner propeller shaft is made tubular and of sufficient size to afford proper passage for the discharge of the exhaust air. The shaft section *E'* is tubular, and forward of the bulkhead *f* it is 15 slightly larger so as to leave a free air space between the two shaft sections. Suitably 20 large perforations *h h'* are formed through the respective shaft sections whereby to admit of a free flow of the exhaust air from the chamber or passage *G* into the bore of the shaft section *D'*. Thus, while the shafts are 25 revolving in opposite directions the exhaust air has unobstructed flow from the chamber *G* through the perforations *h'* into the space between the shaft sections and thence 30 through the perforations *h* into the bore of the inner shaft section and thus out to the stern.

The construction thus described has the 35 advantage of enabling the shafts *D* and *E* to be made of small diameter through the after-body. Where the exhaust is passed through the shafts these are required to be made of large diameter, which makes it difficult to properly pack against leakage in 40 the bearing through which they pass in emerging from the after-body. This bearing requires a packing or stuffing box to prevent leakage of water into the torpedo hull. The 45 use of large tubular shafts also increases the friction in this bearing. This bearing is lettered *H* in Fig. 2 and comprises bearing surfaces proper and a water packing or stuffing box *i*. The present invention thus 50 keeps the shafts of the minimum diameter where they pass through this bearing, and confines their enlargement for the discharge of air to the portion aft of this bearing. The advantage of this construction increases 55 with the increase in the power of the motor and the consequent increase in the exhaust therefrom.

The shaft sections *D'* *E'* are carried in a bearing *I* in the tail section. The proper 60 lubrication of the outer shaft in the bearings *H* and *I* and the inner shaft where it turns within the outer shaft at the same points presents a difficult problem. For the lubrication of the bearing *H*, I provide an oil-cup *K* from which a pipe *j* leads into the bearing and communicates through ducts to the bearing surfaces, and thence through holes *k* in the outer shaft to the bearing surfaces supporting the inner shaft. For 65 supplying oil to the bearing *I* an oil-cup *L*, Fig.

1, is provided from which leads a pipe *l* which extends to a check valve *m* and thence a pipe *l'* leads to the bearing *I*, discharging into an oil groove or channel *n* which encircles the bearing and from which the oil passes through ducts to the bearing surfaces, and thence through holes *k'* in the outer shaft to the inner bearing surfaces. The oil might flow from the oil cups *K* and *L* by gravity, but this would not give a sufficiently copious flow to properly lubricate the bearings during the brief period of intense action involved in the run of the torpedo. To cause a forced flow of oil I establish communication between the upper parts of the oil-cups *K* and *L* and the interior of the exhaust chamber *F*, thereby utilizing the pressure in this chamber as a means for forcing out the oil. The oil-cups *K* and *L* are both located in the chamber *F* so that it is only necessary to make a small hole *p* in each above the oil level, whereby to admit air under the pressure prevailing in the chamber *F* to cause an outflow of oil. The check valve *m* prevents any back-flow of oil followed by an inflow of water to the chamber *F* after the run. For convenience in assembling the parts the pipe *l* is provided with a slip joint *q* which makes connection between the pipe *l* and the check valve when the tail section is united to the after-body.

The invention is not necessarily limited to the precise construction thus described in detail, but may be variously modified and varied in proportion, arrangement and structural features or by the omission of certain parts according to any particular requirements.

I claim as my invention:

1. In an automobile torpedo comprising a compressed air motor, oppositely revolving propeller shafts one within the other, a chamber receiving the exhaust from said motor, an oil-cup having a discharge duct leading to a bearing, said cup open to the air pressure in said chamber above the oil level for subjecting the oil to pressure to expel it.

2. In an automobile torpedo comprising a compressed air motor, oppositely revolving propeller shafts one within the other, a chamber receiving the exhaust from said motor, a spring-pressed valve opening from said chamber whereby a back pressure is induced therein by the resistance of said valve, and an oil-cup having a discharge duct leading to a bearing, said cup open to the air pressure in said chamber above the oil level for subjecting the oil to pressure to expel it.

3. In an automobile torpedo comprising a compressed air motor, oppositely revolving propeller shafts one within the other, a chamber receiving the exhaust from said motor, an oil-cup having a discharge duct

leading to a bearing, said cup open to the air pressure in said chamber above the oil level for subjecting the oil to pressure to expel it, and a check valve in said oil duct 5 adapted to prevent any back flow of water through said duct into said air chamber.

In witness whereof, I have hereunto

signed my name in the presence of two subscribing witnesses.

FRANK M. LEAVITT.
